UNITED STATES PATENT OFFICE.

BENJAMIN H. BLOUNT, OF HOUSTON, TEXAS.

ICE RECEPTACLE.

Application filed January 24, 1922. Serial No. 531,376.

To all whom it may concern:

Be it known that I, BENJAMIN H. BLOUNT, a citizen of the United States, residing at Houston, in the county of Harris and State 5 of Texas, have invented certain new and useful Improvements in Ice Receptacles, of which the following is a specification.

This invention relates to refrigerating apparatus, and has for one of its objects to 10 improve the construction and increase the efficiency and utility of the ice holding portions of devices of this character.

With these and other objects in view the invention consists in certain novel features 15 of construction as hereinafter shown and described and then specifically pointed out in the claims, and in the drawings illustrative of the preferred embodiment of the invention;—

20 Figure 1 is a longitudinal section of the ice chamber portion of a refrigerating apparatus of the character employed in retail stores for the storage and display of articles of food to which the improved device is more particularly applicable with the improved ice holders disposed therein.

Fig. 2 is a section on the line 2—2 of Fig. 1.

Fig. 3 is an end elevation of one form of 30 the improved ice holders.

Fig. 4 is a plan view of the form of ice holder shown in Fig. 3.

Fig. 5 is an enlarged sectional detail illustrating the coupling between the body portion 35 and the rim portion of the form of ice holder shown in Figs. 3 and 4.

Fig. 6 is a sectional detail illustrating the construction of the corner clips for the ice holder structure.

40 Figs. 7 and 8 are enlarged details illustrating a modified construction of the ice holder.

Fig. 9 is an enlarged perspective view of one of the corner holding clips.

The improved device may be employed in 45 connection with refrigerating devices of various kinds, but is more particularly adapted for use in the class of cold storage counters employed in retail stores for the reception and display of articles of food, 50 and for the purpose of illustration is shown thus employed.

The combined counter and display receptacle is generally formed of an intermediate food receiving portion having a glass top 55 10 and glass front, not shown, and with a closed insulated bottom 11 and back 12,

and a closed ice chamber at one or both ends, the latter having insulated walls 13 and cold air passages 14 between the ice chamber and the food receiving chamber. 60 The ice chamber is provided with a door 15 at its front to provide access thereto.

Extending between the rear and front walls of the ice chamber and near the side walls are rail members 16 attached by 65 brackets 17 to the inner faces of the rear and front walls, as shown.

The rails 16 provide combined supports and guides for novel forms of ice holders or baskets, each holder including an oblong 70 frame with the members L-shaped transversely and with two of the opposite frame members bearing upon the rails and supported thereby.

The body of the receptacle or "basket" 75 portion is preferably formed of woven wire or metal strips as may be preferred and represented conventionally at 19, and rolled at their upper edges around an endless binder rod 20, the latter being large enough 80 to rest upon the upper horizontal web of the frame 18, as represented in Figs. 3, 4 and 5.

The body portion 19 of each receptacle is formed from a single oblong sheet or section of the woven material, preferably of metal strips, as shown, with the corners of the sheet cut out to produce a central portion and four lateral portions and bent at right angles to the central portion, the 90 central portion forming the bottom and the lateral portion forming the sides and ends of the receptacle.

At their juncture the edges of the bent up portions are united by clips 21 at suitable 95 intervals.

The clip devices are constructed as shown initially in Fig. 9, and inserted through the interstices in the woven material next to the adjacent edges and the terminals 22 bent 100 over against the adjacent portions of the woven material, as represented in Figs. 6 and 9.

By this means a strong and durable receptacle is provided which may be constructed of any suitable size or material and which may be utilized to contain ice or ice 105 combined with rock salt, to serve as a refrigerant to the air within the ice chambers, and which may be readily removed and inserted through the opening closed by the 110 door 15.

The frame 18 being separate and distinct from the body of the "basket" or holder, the latter can be separated therefrom for cleansing or repairs.

5 The receptacles or baskets may be of any size or capacity and any required number may be employed within the ice chamber.

In Figs. 7 and 8 a slight modification in the construction is shown consisting in substituting for the continuous frame 18 two rail members 22, preferably of L-bars, and connected at their ends by rods 23. The vertical webs of the members 22 are provided with spaced slots or apertures 24 through which the upper ends of the adjacent members of which the body portion of the "basket" is formed are "clinched" as shown at 25, while the upper ends of the basket members adjacent the rods 23 are 20 rolled around the latter as shown in Fig. 7.

The members 22 rest upon the rail members 16 in the same manner as the frame members 18 rest upon the structure shown in Figs. 3, 4 and 5.

25 The modified structure may be employed

under certain conditions but does not constitute a departure from the principle of the invention or sacrifice any of its advantages.

The preferred embodiment of the invention is disclosed in the drawings and set forth in the specification, but it will be understood that modifications within the scope of the claimed invention may be made in the construction without departing from the principle of the invention or sacrificing any of its advantages.

Having thus described the invention, what is claimed as new is:—

An ice receptacle having woven metal 40 walls, a binder for the upper edge of the receptacle comprising spaced end rods over which the vertical strands of the ends of the woven walls are rolled, and spaced side members each perforated to receive the ends 45 of the rods and apertured to receive the vertical strands of the sides of the woven walls.

In testimony whereof, I affix my signature hereto.

BENJAMIN H. BLOUNT.
